UNITED STATES PATENT OFFICE

CHARLES H. RAY, OF LITTLE ROCK, ARKANSAS

STREET SWEEPING MACHINE

Application filed November 12, 1928. Serial No. 318,947.

The object of my invention is to provide a construction of brush which will have important advantages in its action on the dirt or litter to be swept and will have such advantages especially in an embodiment thereof in a street sweeper, such for example, as the type having a pavement-engaging, rotary cylindrical brush and which besides sweeping the surface to be cleaned, collects or accumulates for transportation by the machine the litter or spoils, these being known in the trade as pick-up sweepers.

My invention consists in whatever is described by or is included within the terms or scope of the appended claims.

In the drawing:

Fig. 1 is a side elevation showing an embodiment of my invention in a street sweeper of the pick-up type, that embodiment being what I now regard as a most satisfactory construction and which will utilize or secure the advantages hereinafter mentioned;

Fig. 2 is a top plan view somewhat diagrammatic of the brush of such machine;

Fig. 3 is a detail view in perspective of a portion of the brush on a larger scale;

Fig. 4 is a similar view to show a different manner of attaching the flat-sided bristles to the brush back.

In the embodiment of my invention illustrated in the drawing, is employed what is substantially a motor truck, in that it has the general characteristics of such a truck, namely, a power plant 10, driver's seat 11, chassis 12, and transporting wheels 13, upon which are mounted the various members of a street sweeper of the pick-up type organization and thus the machine is transported and power is supplied for revolution of the rear brush or broom 14, and for movement of those members of the organization which, in the sweeping operation, require to be in motion for performing their respective functions. Since my invention which forms the subject of the claims is concerned with the rear brush, it is needless to describe in detail any parts of the machine than that subject-matter.

The pick-up broom or brush 14, is of cylindrical form and is mounted on a central shaft

15, which extends crosswise of the machine and which at opposite ends is supported by means not necessary to be described, by which the brush bodily may be raised and lowered with reference to the pavement surface to be swept and which by means not necessary to be described, may be revolved by power taken from the truck motor as the machine moves over the surface to be swept.

The brush comprises a circular series of radial or substantially radial bristles which at their inner ends are suitably secured to a holder or "back" concentric with the shaft 15, and from which they extend to their outer free sweeping or brushing ends. The radially extending portions of the bristles are straight but they are flexible and elastic so that by contact with the street surface as the brush revolves forward in its lower part, they will flex or bend backward and then passing out of contact with such surface will automatically spring forward by a flipping action so that they will flip or project forward with considerable force the dirt or litter with which they have contact.

The brush bristles are flat with their flat-wise portions perpendicular to the direction in which they move in their flipping action and in the case shown in the drawing those at or towards each end of the brush, have their flat-wise surfaces set obliquely or at such an angle that the effect of their movement in contact with the dirt which they encounter on the pavement surface is to direct the dirt inward from each end of the brush towards the central portion thereof. Those bristles at the central portion of the brush crosswise of the machine, are preferably set so that they throw the material they engage directly forward in the direction of travel of the machine. The described arrangement of the bristles so that those portions at the ends of the brush have their flat dirt-engaging sides oblique and at converging angles which direct the dirt towards the central part of the brush, is of especial utility and advantage with the pick-up type of sweeper shown in the drawing, which includes an elevator 16, situated forward of and close to the brush at its lower end so

that the sweepings are thrown by the brush to such elevator, thence to be transported in the machine for final delivery to a sweepings receptacle or container 17, not requiring to be described. Such an elevator which is of conventional construction including an endless apron and flights, extends cross-wise of the machine and from a point close to the pavement surface upward and forward and since the sweepings are delivered thereto only from the central portion of the brush, it may be considerably narrower than the length of the brush. The important and practical advantage of this fact will at once be appreciated when it is pointed out that it means saving in cost of construction since instead of elevating mechanism of a width of from six to seven feet which is a common width, the elevating mechanism in a machine embodying my invention having a pick-up brush about sixty inches long may be as narrow as twenty-eight inches. Besides difference in first cost of elevator construction, there is a great saving in weight, not only on account of the diminished weight of the elevator mechanism itself, but on account of the supporting structure of the machine which must have a size and weight suitable to the weight of the machine elements to be carried thereby; and, of course, the lightening of the weight of the entire structure is important because it obviates the danger of damage to gutters and curbs and other objects when the machine is heavy and unwieldy. Again, excessive width of the machine is objectionable because of traffic considerations, for an abnormally wide structure will bottle-neck streets and increase the hazards of traffic.

Again, with the conventional or known construction of pick-up street sweepers, there is a tendency to leave on the street surface streaks or lines of unsightly litter in executing a turning movement as when passing a vehicle parked at the curb and in making hairpin turnings. With a brush having my arrangement of flat-wise resilient or elastic strips, the litter is directed into and kept in the pick-up path.

In street sweeping machines which do not pick up the litter, it is the practice to place the cylindrical brush obliquely to the line of travel for the purpose of giving the sweepings a forward and lateral movement.

An obliquely placed brush obviously requires a greater length of brush than is the case when as with my invention, the brush axis is at right angles to the direction of travel of the machine, and such greater length means great weight and great manufacturing cost. Again, an obliquely arranged brush requires a longer and more cumbersome chassis than one that is at right angles or substantially at right angles to the line of travel of the machine, and it com-

plicates the transmission of power to the brush to revolve it.

For use with sweeping machines which do not pick up the litter but direct the sweepings to the gutter or side of the street, all of the bristles from one end of the brush to the other may be placed with the flat sides inclined or oblique at the same angle so that the sweepings as the brush revolves and the machine moves forward will be directed forward and obliquely towards one end of the brush and beyond the same.

I make no claims herein to any particular way of securing the bristles of the brush to the brush back. It is, therefore, not necessary to show in detail any particular construction in this regard. However, as shown in Fig. 3, the bristles 19 have their inner ends seated in a back in the form of a bar 18, a plurality of such bars being supported in a way, not necessary to be shown in detail, concentric with the brush shaft. Or the arrangement shown in Fig. 4, may be employed where the back is made up of bars in the form of cylindrical segments 20 that are provided with holes arranged in pairs through which the bristles 21 are threaded in hairpin form.

What I claim is:

1. A brush mounted for rotation on a horizontal axis having bristles extending radially outward, said bristles having flattened outer portions whose extremities contact with the surface to be brushed, said bristles being flexible to spring in directions crosswise of the brush axis, the flattened surfaces of the bristles at the central portion of said brush, being substantially parallel with the brush axis, and those at the ends of said brush being oblique to the brush axis.

2. As a means for displacement of dirt from a street surface to be cleaned, the combination of a traveling brush support, a brush comprising bristles and bristle holder to which the bristles are attached so as to project towards the surface to be cleaned to contact therewith at their outer ends, the bristles being resiliently flexible enough to bend backward when in contact with such surface, and then flip forward thereover to exert a propelling force on loose dirt on such surface, the bristles having flat forward dirt-engaging sides, such flat sides being oblique to the direction of travel of the brush support over the street surface and the forward flipping movement of the bristles being perpendicular to such flat sides whereby the dirt engaged and propelled is moved crosswise of the direction of travel of the brush as a whole.

3. A brush comprising bristles and bristle holder to which the bristles are attached and from which they project for contact of their free ends with a surface to be brushed, the

bristles being resiliently flexible enough to bend backward when in contact with the surface to be brushed, and then flip forward thereover, the bristles being flattened with 5 the plane of the flat surfaces perpendicular to the direction of bending movement of the bristles, and means for supporting the brush for movement over the surface to be brushed, the flat surfaces of the bristles being 10 oblique to the direction of travel of said supporting means and the axis of the brush being perpendicular to said direction of travel.

4. In a street sweeping machine of the 15 pick-up type, the combination of a traveling brush support, a cylindrical brush mounted for rotation on a horizontal axis on said support and a dirt-receiving apron having a movement in the direction of travel of said 20 support and having a width in the direction of the length of the brush substantially less than the length of the brush and situated substantially at the longitudinal center of the brush, said brush having bristles extending radially outward, said bristles having 25 flattened outer portions whose extremities contact with the surface to be brushed, said bristles being flexible to spring in directions crosswise of the brush axis, the 30 flattened surfaces of the bristles at the central portion of said brush being substantially parallel with the brush axis, and those at the ends of said brush being oblique to the brush axis.

35 In testimony whereof I hereunto affix my signature.
